UNITED STATES PATENT OFFICE.

HARRISON E. PATTEN, OF SILVER SPRING, MARYLAND.

APPARATUS FOR IMPREGNATING LIQUIDS WITH GAS.

1,216,722.

Specification of Letters Patent. Patented Feb. 20, 1917.

Application filed July 29, 1915. Serial No. 42,664.

(DEDICATED TO THE PUBLIC.)

To all whom it may concern:

Be it known that I, HARRISON E. PATTEN, a citizen of the United States, and an employee of the Department of Agriculture 5 of the United States of America, residing in the county of Montgomery, State of Maryland, (whose post-office address is Silver Spring, Montgomery county, Maryland,) have invented a new and Improved Apparatus for Impregnating Liquids with Gas.

This application is made under the act of March 3, 1883, Chapter 143 (22 Stat. 625), and the invention herein described and claimed may be used by the Government 15 of the United States or any of its officers or employees in the prosecution of work for the Government, or any person in the United States, without payment to me of any royalty thereon.

The object of my invention is to provide 20 an apparatus, which is specially adapted for conveniently and thoroughly charging liquids, such as water, non-alcoholic light drinks, wines, beer, and the like, which are 25 deficient or partly deficient in gaseous matter, with gas under pressure in any desired amount.

My apparatus consists principally of a stirrer connected to a rotary shaft set within 30 a specially designed stuffing box; an extension shell bears a side tube at its lower end through which gas may be admitted to the bottle or other container. On a T-union is mounted a pressure gage of any 35 suitable type to indicate the degree of gas pressure. Suitable valves for entrance and exit of gas are provided, as well as a clamp and other necessary fixtures to secure the charging apparatus in place upon the neck 40 of the container which holds the liquid.

The nature, characteristic features, and scope of my invention will be more readily understood from the following description taken in connection with the accompanying 45 drawings forming a part hereof, wherein:

Figure 1 is a perspective view of my apparatus.

Fig. 2 is a cross section of the same.

Referring to the drawings, A represents 50 a forked spring stirrer having each tine twisted on its longitudinal axis so as to give the liquid a rotary thrust as well as a vertical impetus. The shaft, B, of the stirrer runs in a loose sleeve, C, which is 55 forced through a stopper, D (made of rub-

ber or any suitable material), of proper size for the container holding the liquid to be impregnated with gas. In order to hold the stopper, D, firmly in place, I provide a plate, E, which is fitted over the sleeve, C, before adjusting the stopper, D, in place. Said plate, E, is held tight to the container by means of suitable clamps, a, thereby enabling the stopper, D, to sustain a very considerable gas pressure from within the container. The dimensions of plate, E, may be varied to suit the style of clamp used; and the style of clamp required will depend upon whether the charging device is to be used as a single unit, or multiplied into a 70 battery and driven by a common gear with separate disengagement clutches for each unit stirrer; the size and style of container used will also influence the design of the clamp. Shaft, B, passes upwardly through the loose sleeve, C, and through a stuffing box of the special design (or other suitable design), disclosed in Fig. 1 of the drawings, consisting of several parts, namely, a thick collar, Q, whose upper end is shaped 75 to form a hexagonal nut, G, which slides freely upon shaft, B, and is externally threaded at its lower end to screw into the stuffing box shell, F. The shell, F, has a shoulder, b, inside, just above the insertion 80 of tube, J, which serves to retain a packing of oil-soaked lamp-wick, or other suitable packing material which is squeezed tightly against the shaft, B, when the hexagonal end of the collar, Q, is turned down with a 85 wrenching tool. This stuffing box serves to 90 form a gas-tight joint between the shaft, B, and the outside shell, F, of the stuffing box while still permitting rotary motion. The hexagonal nut, G, and collar, Q, permit a screw adjustment of pressure on the 95 packing in the stuffing box. The shaft, B, as it emerges from the stuffing box, F, is fitted with a pulley, H, which is in turn 100 belted to a motor of convenient dimensions, type and power. The shaft, B, may also be fitted with gear-drive and disengagement clutch of convenient design, or may have direct connection with a suitable motor of any desired motive power, such as gas, 105 steam, electricity, compressed air, gasoline, or the like.

The side tube, J, is set into the extension shell of the stuffing box, F, so that its opening connects with the cylindrical space be- 110

tween the loose sleeve, C, and the shaft, B, thus giving a gas inlet into the container. The solid lug, J, opposite to side tube, J, is integral with J and serves as a handle in 5 manipulating the apparatus. A threaded union, N, serves to connect the apparatus with a source of gas; the entering gas then passes through the valve, O, and then by way of the unions, K and P, through the 10 side tube, J, and thence through the loose sleeve, C, into the air space in the container.

The side tube, M, serves to withdraw gas, at will, from the container, and is closed by 15 the reseating valve, L.

In order to read and control the pressure in the container, a gage of any convenient type, U, is connected to the upper thread of the T-union, K. Where several stirrers 20 are connected in a battery, one gage may be used to read the common line pressure of gas, or a gage may be connected to each as desired.

The charging apparatus operates as follows: Water (or other liquid) is run into a 25 container of suitable dimensions and strength. The tines of the stirrer, A, are pressed together, if necessary, and inserted in the mouth of the container. The stopper, D, is then pressed in place in the container, and the plate, E, is firmly clamped to the container. A source of gas of any 30 convenient type furnishing the gas under any desired pressure, is connected by a 35 screw-union, at N, to the charging apparatus. The gas is then turned on and the stirrer, A, is rotated rapidly either by belt or by direct connected motor until the gage, U, shows a satisfactory degree of pressure. The 40 degree of required pressure in the container is indicated by the gage, U, after which indication the valve, O, is closed to prevent further entrance of gas from external source into the container. The container may be 45 maintained at any desired temperature during this operation of impregnation with gas. By opening valve, L, the gas above the liquid may be run off and foreign gases present in the container may be gradually displaced by carbondioxid or other gas for the 50 impregnation by alternately opening and closing the valves O and L. When the

liquid has been sufficiently charged, the stirrer is removed from the container and the container may be closed in any suitable 55 manner.

From the foregoing, it is thought that the construction, operation, and many advantages of the herein described invention will be apparent to those skilled in the art, without further description, and it will be understood that various changes in the size, shape, proportion and minor details of construction may be resorted to without departing from the spirit or sacrificing any 65 of the advantages of the invention.

Having thus described my invention, I claim:

1. An apparatus for impregnating liquids with gas, comprising a pipe for supplying 70 and exhausting gas, a stopper, and a stuffing box carried by said pipe, a rotary shaft passing through the stuffing box and pipe, a stirrer carried by the shaft, and means for clamping the stopper in the mouth of a 75 receptacle.

2. An apparatus for impregnating liquids with gas, comprising a pipe for supplying and exhausting gas, a stopper and stuffing 80 box carried by the pipe, a rotary shaft passing through the stuffing box and pipe, a stirrer carried by the shaft, valves for controlling the entry and escape of gas, means for rotating such shaft, and means for 85 clamping the stopper in the mouth of a receptacle.

3. An apparatus for impregnating liquids with gas, comprising a stirrer, stopper, a gas-tight stuffing box and a sleeve, a rotary shaft carrying said stirrer and operating in 90 said stuffing box and sleeve, a pulley for rotating said shaft, a pipe for supplying and exhausting gas, provided with valves, means for controlling the entry and escape of gas, and means for clamping said stopper to a 95 container.

In testimony whereof, I affix my signature in the presence of two subscribing witnesses.

HARRISON E. PATTEN.
